UNITED STATES PATENT OFFICE.

EDWARD A. WILDT, OF SCRANTON, PENNSYLVANIA.

DUMPING-GRAVE.

1,100,412.

Specification of Letters Patent. Patented June 16, 1914.

Application filed January 25, 1913. Serial No. 744,226.

To all whom it may concern:

Be it known that I, EDWARD A. WILDT, a citizen of the United States, residing at Scranton, Lackawanna county, State of Pennsylvania, have invented certain new and useful Improvements in Dumping-Grates; and I do hereby declare the following to be a full, clear, and exact description of the invention, such as will enable others skilled in the art to which it appertains to make and use the same.

My present invention relates to the rocking sections of dumping grates which are used for burning fine grades of coal, culm, etc., and it is particularly directed to the construction of a dumping grate section which is not subject to the warping usually incident to the cumulative effect of the unequal expansion of the several parts of the grate sections, and particularly noticeable as between the hot fire surface and the under surfaces of the grate which are cooled by the air blast. This warping of the grate sections produces an uneven grate surface and a mismatching of the sections resulting in the occurrence of openings of greater area, at various regions throughout the surface of the grate, through which the air draft or blast, as the case may be, rushes in undue volume precluding the maintenance of an evenly distributed fire upon the grate; and may cause such a distortion of the sections that they interfere and will not close properly, and finally break.

I have illustrated a grate section constructed in accordance with the present invention in the accompanying drawings, in which—

Figure 1, is a view in perspective of the grate section; Fig. 2 is a bottom plan of the same; Fig. 3 is a section on line 3—3 of Fig. 2, and Figs. 4 and 5, are details in perspective showing the two sides of one of the units employed.

Referring to the drawings, my grate section is made up of two end plates A and B which are each provided with a trunnion C projecting from their outer surface, and a plurality of stacks D of interlocking grate units E, which may be, for instance, of the configuration shown in Figs. 4 and 5, the end units of which stacks interlock with the end plates A and B and are held therebetween by tie rods F, the heads or nuts G of which are received in countersinks H in the outer surfaces of the end plates A and B.

The upper surface of each of the grate units E terminates at one end in an overlap I and at the other end in an underlap J and the overlaps I of the units E in one stack D of said units engage underlaps J of the units E in the next adjacent stack D of units E. When the grate section is completely assembled as in Fig. 1, the overlaps I of the units of one end stack will form one edge of the grate section, and the underlaps J of the units in the opposite end stack will form the opposite edge of the grate section so that when two or more grate sections are placed in the furnace each will be provided with an overlapping edge and an underlapping edge which will engage with the adjacent grate sections to avoid apertures at the junctions of the sections when the grate is closed.

A dumping crank K is assembled at a suitable point with the grate units E and serves for the connection of a bar by which the section may be rocked.

It is evident that there will be no rigid members extending throughout the length of the grate section and, since each unit is separate from the adjacent unit, that warpings due to expansion and contraction will not be accentuated beyond the particular unit wherein they occur. A great advantage is also obtained by the construction shown in that the entire section may be disassembled at any time and new units substituted for burned parts whereby the considerable expense entailed in the purchase of an entire grate section when a portion only is destroyed is materially reduced.

What I claim and desire to protect by Letters Patent is:

1. A dumping grate-section comprising a plurality of stacks of interlocking grate units, separate end plates embracing the ends of several stacks of units and tie rods connecting said end plates and maintaining the embrace of said several series of sections by said end plates; substantially as described.

2. A dumping grate section comprising a plurality of stacks of interlocking grate units and separate one-piece end plates common to all of said stacks of units; substantially as described.

3. A dumping grate section comprising a plurality of stacks of interlocking grate units and separate trunnioned one-piece end plates common to all of said stacks of units; substantially as described.

22

4. A dumping grate section comprising a plurality of stacks of interlocking over-lapping grate units and separate one-piece end plates common to all of said stacks of units; substantially as described.

5. A dumping grate section, comprising a plurality of over and under lapping stacks of interlocking grate units, each of said units having an overlap upon one end of its fuel supporting surface and an underlap upon the opposite end of its fuel supporting surface; substantially as described.

10. A dumping grate section, comprising a plurality of over and under lapping stacks of interlocking grate units, each of said units having an overlap upon one end of its fuel supporting surface and an underlap upon the opposite end of its fuel supporting surface, and separate one-piece end plates common to all of said stacks of units; substantially as described.

15. A dumping grate section, comprising a plurality of over and under lapping stacks of interlocking grate units, each of said units having an overlap upon one end of its fuel supporting surface and an underlap upon the opposite end of its fuel supporting surface, separate one-piece end plates common to and interlocking with the end units of all of said stacks, and tie rods connecting said end plates; substantially as described.

20. A dumping grate section comprising a plurality of slidably over and under lapping stacks of interlocking grate units, and separate one-piece end plates common to and interlocking with the end units of all of the said stacks; substantially as described.

25. A dumping grate section comprising a

plurality of slidably over and under lapping stacks of interlocking grate units, and separate one piece end plates common to and interlocking with the end units of all of said stacks, said end plates having overlaps on one end of their fuel supporting surfaces and underlaps on the opposite ends of their fuel supporting surfaces to correspond with the exposed overlaps and underlaps of the units of the first and last stacks; substantially as described.

30. A dumping grate section comprising a plurality of slidably over and under lapping stacks of interlocking grate units, each of said units having an overlap at one end of its fuel supporting surface and an underlap at the opposite end of its fuel supporting surface, trunnioned end plates common to and interlocking with the end units of all of said stacks, said end plates having overlaps at one end of their fuel supporting surface and underlaps at the opposite end of their fuel supporting surfaces to correspond with the exposed overlaps and underlaps of the units of the first and last stacks, and a tie rod passing through apertures in the units of each stack and connecting said end plates, said end plates having depressions in their outer surfaces for the flush reception of the heads and nuts of said rods, substantially as described.

35. In testimony whereof I affix my signature, in presence of two witnesses.

EDWARD A. WILDT.
